PRODUCTION OF LACE, NET, OR THE LIKE

Albert Edward Hunter, Wollaton, Nottingham, England, assignor to Bayard Manufacturing Company, Limited, Nottingham, England

Application February 12, 1940, Serial No. 318,583
In Great Britain December 15, 1938

4 Claims. (Cl. 96—20)

This invention comprises improvements in or relating to the production of lace, net or the like and has more particular reference to the production of hair-nets or the like.

5 In the manufacture of lace or similar fabric on a twist lace machine, it is usual to produce web across the full width of the machine, there being a number of breadths of web laced together with lacing threads, and the whole being 10 wound either direct on to a work roller, or on to a porcupine roller and thence to a work roller; said work roller being put out of gear for the removal of the web therefrom after the required length has been produced.

15 When making hair-nets, the web is produced in a large number of comparatively small breadths, in some cases as many as 150 breadths, each having elastic woven or threaded under tension along each side edge of each breadth; 20 consequently, it will be appreciated that a large number of breadths with tensioned elastic so produced cannot be removed from the work roller in the same manner as a web of ordinary lace or net.

25 Heretofore it has been usual to transfer the several breadths of fabric for the hair-nets or the like to a roller outside the machine, the net breadths being removed from this roller by various methods and made up into suitable form for dyeing.

30 Broadly the present invention provides a machine for manufacturing hair-nets or the like in the form of a plurality of breadths, having at least one winding-on member on to which 35 the several breadths are wound side by side, characterised in that said member is so constructed or arranged as to permit of said breadths being readily and individually removed therefrom in a form suitable for dyeing.

40 The invention also includes in or for a machine for the manufacture of hair-nets or the like in a plurality of breadths, means, including at least one member on which the fabric is accumulated during its manufacture, whereby the 45 fabric may be made up into skeins on the machine itself.

According to a preferred arrangement the invention comprises a machine, e. g. a twist lace machine, for the manufacture of hair-nets or the like, having associated and operating therewith at least one skeleton reel or skein winder, and means for winding the net on said reel during manufacture, which said reel is collapsible, or constructed so that the diameter or compass 50 thereof can be reduced, so as to permit of the

ready removal of the material therefrom when the required length has been produced.

In order that the invention may be better understood, reference will now be made to the accompanying drawings, in which:

Figure 1 is an elevation, partly in section, of a twist lace machine according to this invention, while

Figure 2 is an elevation of certain parts thereof, looking in the direction of arrow 2 in Figure 1. 10

In the accompanying drawings the lace making mechanism of the machine is not illustrated in any detail, nor is it described herein, since it is of well understood form. It will suffice to say that the narrow widths of lace N (produced 15 simultaneously, with tensioned elastic thread incorporated at the edges of each width, but preferably without the draw threads or lacing threads that are sometimes worked-in to connect the edges of successive breadths of lace 20 net in a plurality of simultaneously-produced breadths) pass upwards over the face of the guide bar 10 to the porcupine roller 11. In the manufacture of breadths of hair-net as practised prior to this invention the net is wound 25 onto a roller which is indicated in dotted lines at 12 and rests upon the porcupine roller 11. When this roller 12 is full it is customary to set up at the front of the machine a small diameter rod in substantially the position indicated in 30 dotted lines at 13. This rod extends for half the length of the machine. The ends of the hair-net which, in that half length, are wound upon the roller 12, are then taken by hand from 35 said roller and are attached to the rod 13 which is thereafter rotated by means of a crank handle to wind the nets on to it. When all the fabric has thus been transferred the rod is removed from the machine and is hung up in any convenient place and the fabric is pulled off it by 40 hand. The consequent bundle of net fabric is sorted out by hand and each length is coiled or wound onto a loose ring-like coil to form a skein, the ends being tied for safety.

According to the present invention, instead of 45 the various lengths of net being wound side by side on to a roller, such as 12, they are conducted downwards at the back of the porcupine roller 11, preferably over a small guide roller or rod 14 situated at a lower level than said porcupine 50 roller 11 and a suitable distance rearwardly thereof, the disposition of this guide roller or rod 14 being such as to enable the nets to clear the moving parts of the machine. From this guide roller or rod 14 the nets are then passed 55

- beneath a roller 15 covered with thick cloth, felt, rubber or other suitable material, which may conveniently be located under the back rail 16 of the machine, say about two feet below same.
- 5 This last-named roller 15 is advantageously of comparatively large diameter, say for example about 6" in diameter, and is driven at a speed considerably in excess of the speed of the porcupine roller 11 (e. g. by belt 17 from shaft 17a).
- 10 The cloth-covered or like roller 15 may be rotated in the same direction as the porcupine roller 11, the nets being passed down to the rear of said cloth-covered roller, then beneath same and upwardly in a rearward direction. By driving the 15 cloth-covered or like roller at a greater speed than the porcupine roller, the nets are kept taut and clear themselves from the said porcupine roller; said cloth-covered or like roller acting in the manner of a brush.
- 15 Conveniently spacing points 15a are provided cooperating with the roller 15, for keeping the edges of the lengths separate.

Situated at the back of the machine and advantageously above the level of the back rail 16, 25 there is at least one skeleton reel indicated generally by the numeral 18. This skeleton reel is collapsible in that its diameter or compass may be reduced after the net has been wound on to it so that the lengths of net may then be readily 30 removed as separate loose skeins. There may be one such reel or skein winder extending for the whole length of the machine, but preferably there is a plurality thereof located end to end. In the illustrated construction there are two of them as is clearly shown in Fig. 2. These winders are rotated by means of a clawker 19 which is mounted on an oscillating arm 20, the said arm being oscillated by a connecting rod 21, lever 22 and a cam 23. The connections are such that 40 the stroke of the clawker 19 is adjustable. The said clawker 19 co-operates with a ratchet wheel 24, and a locking clawker 25 (co-operating with a ratchet wheel 25a) is also provided to prevent reversal of the motion of the winders 18. The 45 said ratchet wheel 24 is arranged to drive the skein winders 18 through a frictional coupling of any suitable form.

It will be seen that each skein reel or winder 18 consists of a number of longitudinally extending bars 26 mounted on radial spokes 27. At 50 least one bar, indicated at 26', has its spokes 27' pivotally mounted so that after the lengths of net have been wound on to the skeleton reel the said bar 26' may be swung towards one of the 55 adjacent bars and the compass of the reel thereby reduced, permitting the lengths of net to be removed from the reel one by one after they have been tied.

Preferably one of the bars 26 adjacent to the 60 bar 26' is provided with spacing points 28 so that during the production of the net the various lengths thereof are maintained separate.

The manner in which the skeleton reels 18 are 65 removably mounted in the machine is also shown in Fig. 2. The ratchet wheel 24 drives a socket member 29 through a frictional coupling (not shown) which is conveniently adjustable by means of nuts indicated at 30. This mechanism is permanently journalled in the machine frame. 70 The socket member 29 has an axial socket for the reception of the shaft 31 of one of the skeleton reels, which shaft when in position is arranged to be driven from the socket by means of a pin 32 which is received in a slot in said 75 socket member. This arrangement therefore

provides a readily-separable coupling, one portion 29 of which is left in situ in the machine when the reel 18 is removed. At its other end the shaft 31 is removably supported in a split bearing 33 having a readily removable bearing 5 cap 33'. At said end the shaft 31 is also provided with one member 34a of a dog coupling whereby the shaft 31 may be connected to a shaft 31' of the next collapsible reel. This shaft 31' is provided with the other member 34b of the 10 dog coupling and at its ends is supported in split bearings 35, 36, the respective caps 35' and 36' of which are readily removable.

It will therefore be appreciated that each of the collapsible reels may be readily removed from 15 and returned to its operative position in the machine. Each reel is conveniently collapsed after it has been removed from the machine, so that after said removal and collapse the lengths of net may be removed therefrom one by one in 20 the form of skeins, ready for dyeing. Desirably, before removal, each length of net is tied to prevent it becoming unwound.

As has already been stated, the speed of rotation of the roller 15 is in excess of that of the 25 porcupine roller 11 and the stroke of the clawker 9 is adjustable. These two features are of considerable importance in the carrying out of the invention.

It is essential that the nets be manufactured 30 with the elastic in a stretched condition; that is, that the elastic be fed to the points of the machine under tension. By virtue of the fact that the speed of the roller 15 is in excess of that of the porcupine 11, one ensures that the 35 tension of the elastic is maintained and that the hairnets pass from the porcupine to the roller 15 with the elastic threads in a tensioned condition. It is, however, essential that they should be wound on to the reel or skein winder 40 in a substantially relaxed condition and it is for this reason that the stroke of the clawker 19 is made adjustable. The stroke will be varied according to circumstances to ensure that the elastic threads of the hairnets, after passing 45 the roller 15, relax and the hairnets are wound on to the reel in the relaxed condition.

I claim:

1. In a machine for the simultaneous production of a plurality of strips of lace, net or 50 like fabric having elastic threads incorporated therein, said machine including a porcupine roll driven at a predetermined speed about which the finished strips pass, the combination of a second roll about which the strips are trained 55 upon leaving said porcupine roll; means for driving said second roll at a higher peripheral speed than that of said porcupine roll; and a reel for receiving the fabric strips from said second roll.

2. In a machine for the simultaneous production of a plurality of strips of lace, net or like fabric having elastic threads incorporated therein, said machine including a porcupine roll driven at a predetermined speed about which 65 the finished strips pass, the combination of a second roll having a friction covering about which the strips are trained upon leaving said porcupine roll; means for driving said second roll at a higher peripheral speed than that of 70 said porcupine roll, whereby the elastic threads may be tensioned between the two rolls; and a skeining reel for receiving the fabric strips from said second roll.

3. In a machine for the simultaneous produc- 75

tion of a plurality of strips of lace, net, or like fabric having elastic threads incorporated along the edges thereof, said machine including a porcupine roll driven at a predetermined speed about which the finished strips pass, the combination of a second roll having a friction covering about which the strips are trained upon leaving said porcupine roll; means for driving said second roll at a peripheral speed higher than that of said porcupine roll, whereby the elastic threads may be tensioned between the two rolls; a skein-

ing reel for receiving the fabric strips from said second roll; means for driving said reel; and means for controlling the speed of said reel whereby the tension on said elastic threads may be relieved.

4. A machine according to claim 3, in which the means for driving the skeining reel includes a ratchet wheel and a clawker, and the means for controlling the speed of the reel comprise means for adjusting the throw of the clawker. 10

ALBERT EDWARD HUNTER.
